UNITED STATES PATENT OFFICE.

JOHN H. STEVENS, OF SANDWICH, MASSACHUSETTS.

WEIGHING-SCALE.

SPECIFICATION forming part of Letters Patent No. 319,637, dated June 9, 1885.

Application filed March 2, 1885. (No model.)

To all whom it may concern:

Be it known that I, JOHN H. STEVENS, of Sandwich, in the county of Barnstable, State of Massachusetts, have invented a certain 5 new and useful Improvement in Weighing-Scales, of which the following is a description sufficiently full, clear, and exact to enable any person skilled in the art or science to which said invention appertains to make and use the 10 same, reference being had to the accompanying drawings, forming part of this specification, in which—

Figure 1 is a side elevation representing my improved scale in position for use; Fig. 2, a 15 vertical longitudinal section of the hopper detached; Fig. 3, a side elevation of the standard mounted on the hopper of a coffee-mill, and Fig. 4 a front view of the hopper detached.

Like letters of reference indicate corresponding parts in the different figures of the drawings.

My invention relates to that class of weighing-scales which are provided with a beam and hopper; and it consists in a novel construction and arrangement of the parts, as hereinafter more fully set forth and claimed, by which a more effective and otherwise desirable device of this character is produced than is now in ordinary use.

The nature and operation of the improvement will be readily understood by all conversant with such matters from the following explanation, its extreme simplicity rendering an elaborate description unnecessary.

In the drawings, A represents the standard; B, the beam, and C the hopper or vessel for holding the coffee or other article being weighed. The beam, which is of the ordinary construction, is pivoted at x in the standard A, and 35 provided with a horizontally-projecting bifurcated bracket, D, at its forward end. The hopper C is preferably cylindrical in form, and is arranged vertically between the arms i of the bracket D, being provided with an open 40 flaring mouth, d, and at either side with a laterally-projecting stud, f, which has a downwardly-projecting arm, z, said last-named arms passing loosely through holes (not shown) in the arms i, and thereby pivoting or suspending the 45 hopper in such a manner as to enable it to swing 50

or oscillate on a line with the beam B, but not at right angles thereto. The bottom m of the hopper is pivoted or journaled at one side of its center by means of the rod l, which passes horizontally through the body of the hopper, 55 and is provided at one of its ends with the cross head or bar t, the bottom being firmly secured to the rod, and the rod adapted to turn in its bearings in the sides of the hopper. A spring-catch, k, is attached to that side of the 60 hopper which is nearest the beam B, said catch being adapted to hold the bottom m in position when closed. An adjustable stud, r, projects horizontally from the standard A, the object of said stud being to prevent the hopper 65 from swinging too far toward the beam B, when the spring k is pressed outwardly toward the standard A to open the bottom m and dump the contents of the hopper. The standard A has its lower end slotted, as shown at v, and is 70 detachably inserted in a socket, N, attached to the counter M. A table, Q, is mounted on the upper end of a vertically-arranged rod, R, which passes loosely through the counter M, and has its lower end jointed to a treadle, L, 75 pivoted in the standard T, the table being adapted to be raised and lowered, as desired, by means of the treadle and rod.

In the use of my improvement the bottom m is first closed and secured by the catch k, after 80 which the coffee or other article to be weighed is placed in the hopper C and weighed. The bag or other receptacle into which the coffee is to be dumped is then placed on the table Q and raised or lowered, as the case may be, by means 85 of the treadle L, to bring it into proper position with respect to the hopper, after which the spring-catch k is pressed in the direction of the standard A until it releases the bottom m and permits the contents of the hopper to be 90 dumped into the bag in a manner which will be readily obvious without a more explicit description. The standard A is slotted as shown at v, to enable the scale to be attached readily to the hopper H of a coffee-mill, thereby enabling the coffee to be weighed and dumped directly into the mill for grinding. I do not, however, confine myself to the use of the slot for securing the standard to the hopper H, as 95 any other suitable means may be employed. 100

The bar *t* is used for closing the bottom *m* after the contents of the hopper have been dumped.

Having thus explained my invention, what I claim is—

- 5 1. The standard *A*, having vertical slot *V*, beam *B*, and a dumping-hopper suspended within the forked ends of said beam, in combination with the hopper *H* of a grinding-mill, substantially as described.
- 10 2. In a sack-scale, the combination of the standard *A*, the scale-beam *B*, provided with a bifurcated extension, *D*, a swinging hopper, *C*,

pivoted on said extension, and provided with the hinged bottom *m*, and with a spring-catch, *k*, attached to its side for retaining said bottom 15 in closed position, and a stop, *r*, attached to the standard for retaining said hopper in position during the releasing of the catch, substantially as described.

JOHN H. STEVENS.
